MANUFACTURE OF HARMONICAS

Charles E. Wetzler and Paul F. Boehm, Long Island City, N. Y., assignors to The United States Harmonica Corporation, a corporation of Connecticut

Application February 24, 1940, Serial No. 320,646
In Great Britain February 24, 1939

12 Claims. (Cl. 29—34)

This invention relates to musical instruments and more particularly to the so-called mouth organs or harmonicas and to the production thereof. Harmonicas of the conventional type comprise, among other parts, plates with a number of slots and a corresponding number of reeds individually attached to the plates so that each of said reeds can oscillate independently within or through one of said slots. In the assembling of said reeds to the plates, difficulties have been encountered as the conventional means and methods used for that purpose are not at all satisfactory and adequate for mass production.

The invention aims, therefore, to overcome such difficulties and to provide a new method and machine whereby the reeds may be more or less automatically assembled to the plates of harmonicas with great precision and effectiveness and great saving as compared with the prior art.

Further objects and details of our invention will be apparent from the description given hereinafter and the accompanying drawings illustrating the method and an embodiment of the machine according to the invention by way of example.

In the drawings:

Fig. 1 is a top plan view of the embodiment, part of the top being broken away;

Fig. 2 is a cross-section along line 2—2 of Fig. 1 and showing one station of the machine during one particular stage of its operation;

Fig. 2A is a cross-section similar to Fig. 2 illustrating a modification of the machine shown in Figs. 1, 2 and 3;

Fig. 3 is a cross-section along line 3—3 of Fig. 2 of the same station during another stage of operation;

Fig. 3A is a detail view of the cut-off punch included in the machine of Fig. 2A;

Figs. 2B and 3B are longitudinal and cross-sections respectively of the modified bolster plate and gage plate of Figs. 1 and 2;

Fig. 4 shows a portion of the strip material comprising the reed blanks;

Fig. 4a is a similar illustration of a modified form of a reed strip;

Fig. 5 is a top plan view of a plate of a type that may be used in connection with our invention;

Fig. 5a shows the same plate in cross-section and one reed above it in their relative position as occurring immediately before the parts are assembled.

In Figs. 1 to 3 100 represents the main table of the machine which, in the illustrated embodiment, is provided to handle plates with ten slots. The table 100 is of substantially circular shape and supported by bolts 140 on a lower platform 141. In the main table 100 there is a circular groove adapted to hold rotatably an index dial 101 adapted to be turned in angular steps around the center 102. In the present embodiment twelve stations *a* to *m* are provided for the dial. In accordance with the circumferentially disposed twelve stations there are embodied in the dial 101 at regular intervals twelve bolster blocks 103 each being adapted to receive, in a suitable recess of its top surface, a blank plate 104 in such a position that a series of slots 105 provided in each block are in exact alignment with the corresponding slots of the said plate. Below each block 103, the dial 101 is provided with an opening 103, and the main table 100 has similar openings 104 at every one of the stations *b* to *l* inclusive. A tiltable gage member 130 is mounted on hinges 131 close to each of the bolster blocks 103 so that it can be swung into engagement with the recess of the co-ordinate block 103 in a way warranting that a number of slots 106 provided in the gage, 130 will be in accurate alignment with the slots 105 of the respective block 103 and with the slots 104 of a plate positioned in said recess of the particular block 103. The slots 106 of the gage member 130 are extended at their one ends beyond the lengths of the corresponding slots 105 as clearly shown in Fig. 3 and such extensions are so formed as to permit the application of a tool for securing the root of a reed to a plate 104 as will be explained hereinafter.

The reeds may be attached to the plates by any suitable working method such as welding, spot welding, soldering or riveting. In the illustrated example, rivets are used for securing the reeds to the plates, and more particularly rivets which are extruded out of the plate material proper. This is diagrammatically shown in Figs. 5 and 5a where opposite to the one end of each slot 104 of the plate 100 there is a lug or rivet 112 extruded by pressure from underneath during the production of the plates.

The reeds 110 as shown by way of example in Figs. 4, 4a and the upper part of Fig. 5a are of conventional shape when finished and have a rivet hole 111. However, in the production they are originally not blanked out completely but interconnected by a strip-like margin portion 113 as in Fig. 4 or by bridge portion 114 as in Fig. 4a. In either form, the reed material 55 can be fed to the assembling machine as comb-

like strips, and only in the machine the reeds 710 are severed from each other and/or the strip by a small cut either along the dotted line 715 or the dotted lines 716. In the first case the margin strip 717, and in the other case the small pieces 718 go to the scrap. Above the main table 700 and the dial 701 a stationary platform 707 is arranged on supporting studs 732. The platform 707 carries in proper circumferential distribution ten sub-press dies 708 each located above one of the ten stations *b* to *l* of the dial. Only one such die is shown in the plan view Fig. 1 on a portion of the platform 707—the rest being broken away in order to show the parts beneath. At the lower side of said platform 707 a means is provided, in coordination with each of the dies 708, whereby the reed material shown in Fig. 4 or 4a respectively may be fed to the particular die. For this purpose, channel guides 709 are provided which extend from the outside radially towards center 702. The channels are just wide enough to accommodate the particular reed strip including the marginal portion 713, if any. As the reeds 710 move in the direction *z* under the respective die 708 the actually foremost reed is brought to a point where it is exactly in line with the corresponding slot 705 of the bolster block 703, actually being positioned at that particular station, and in line with the corresponding slot 706 of the pertaining gage 730. Again in line with the said slots 705, 706 the channel piece 709 is perforated vertically at 735 so as to permit a reed 710 (when severed from the strip) to be moved vertically downward from the channel 709 to the bolster block 703 or rather to the top side of a plate 704 held in the recess of the bolster.

Each of the sub-press dies 708 is intended to deal with one particular reed only. Therefore, the individual dies 708 are radially offset with respect to each other in such a manner that the center line of every other die will be in alignment with a different slot 742, 705, 706 respectively as a plate 704 travels around stepwise with the dial movement. In other words, while a plate 704 moves step by step from station *b* to station *l* each slot 742 in rotation will stop at the various stations in alignment with the individual dies 708. For instance, in Fig. 2 the die 708 is in alignment with the third slot 742. This is the case at station *c*. At station *d* the fourth slot 742 may be in line with the respective die 708.

Every one of the dies 708 comprises a movable press-head 721 and a punch 723 rigidly attached thereto. The head 721 is properly guided by pins 746. While the punch 723 is primarily intended to cut off the individual reeds 710 from the original strip, and therefore has substantially a cross-section matching the square heel part of the reeds, the head 721 is in addition provided with a spring controlled hold-down 722 whose cross-section substantially matches the shape and size of reed tine proper. Thus, the hold-down is adapted to penetrate through the slot 735 of the pertaining channel guide 709 and through the particular slot 706 of the gage 730. By a spring 747 held and controlled through a screw head 724 in the press head 721, the hold-down 722 is pushed ahead of the punch 723 as is shown in Figs. 2 and 3. If, however, the press-head 721 with the rigid punch 723 is moved down under a force *y* applied in the well-known manner from the top, the hold-down will yield when encountering any resistance.

Below the main table 700 there is a plate 719 movably mounted on a lower platform 741 of the machine in such a manner that it may be moved up and down under the action of, e. g., a set of 5 cams 748 controlled by the same drive which controls the movement of the dial, the feed mechanisms and the sub-press dies. On plate 719 which extends substantially all around the machine below the dial 701, ten plungers 720 10 are fixed at regular intervals corresponding to the positions of the ten stations *b* to *l*, and radially disposed in such a way that each plunger 720 is exactly below the corresponding hold-down 722 and therefore adapted to fit into the pertaining slots 705, 706 and 742 of a bolster block 703, its gage 730 and a plate 704 held therebetween when the dial 701 and therefore the just mentioned parts are in any one of their positions of rest. The arrangement is such that 15 when the plate 719 is in its lowest position the tops of the plungers 720 are just below the lower surface of the dial 701 whereas when the plate 719 is fully raised the tops of the plungers 720 are level with the bottom of the guide channel 20 709 as is shown in Fig. 3.

In practice, the machine operates as follows: The dial 701 is moved around the center 702 in angular steps, in the present instance of 15° each, so as to bring, by each step, each of the blocks 30 703 from one of the stations *a* to *m* respectively to the next following station. During each stop of the dial 701, one new plate 704 is fed at *a*, in the direction of arrow *x*, into the block 703 actually being positioned at *a* while a plate 704 completely filled with all the reeds 710 is delivered 35 at *m*; simultaneously at each of the stations *b* to *l* inclusively, one particular reed 710 is being cut off the pertaining strip (that was fed to the proper point within the particular channel 709) 40 and attached to the plate 704 which just happens to be at the particular station. Thus each plate 704 while travelling around step by step picks up at every station one more reed until all of them i. e. their full number has been collected 45 by each plate 704.

In detail, the operation is as follows: As soon as the dial 701 comes to a standstill after an angular step, on station *a* the gage member 730 50 tilts open and a plate 704 is placed into the recess of the bolster block 703 whereupon the gage closes again; on station *m* the gage 730 opens and the completely filled in plate 704 is taken out of the block 703; while the dial 701 was making its step of 15°, all the reed strips at the stations *b* to *l* were moved forward in direction *z* one step inside the individual channels 709 so as to bring one reed right under the appropriate hold-down 722 and punch 723; now the plate 719 is moved upwards under the action of the 55 cams 748 until it reaches the top position and supports the individual reeds which have reached their positions as just mentioned; then the force *y* is applied to all of the sub-press dies 708 so that the press-heads 721 are moved down; thereby all the hold-downs 722 first engage the corresponding reed 710 from the top, press it on the top of the corresponding plunger 720 so as to clamp it while the springs 747 are more and more compressed until the individual punches 60 723 reach the top of the reed heels (which position is shown in Fig. 3) and penetrating into the die plates cuts the clamped reeds off its strips along the dotted line shown in Figs. 4 and 4a respectively; then due to the continued downward movement of the heads 721, the clamped 65

reeds 710 are moved downwards also together with their supporting plungers 720; of course, the plate 719 and the cams 747 are forced downwardly as well, until the reeds 710 reach the level of the upper surface of the individual plates 704; thereby the holes 711 of these reeds are threaded over the upwardly projecting rivets 712 and the latter are immediately after that spread by the final part of the movement of the punch 723 thus completing the riveting operation. After this, the plungers 720 following the cams 747 move further down into their position of rest shown in Fig. 2, whilst the parts 721, 722 and 723 of the various sub-press dies 708 move back upwardly so as to return to their positions of rest also shown in Fig. 2. Now the dial 701 may make its next angular step.

The above embodiment is merely an example and many alterations and alternatives may be found. For instance, the relative movements of the different parts and elements may be carried out in reverse arrangement, and the rotary movement of the dial may be replaced by the rectilinear movement of a kind of a chain conveyor carrying the different bolster blocks, the feeds and sub-press dies being lined up along the path of such conveyor. Of course, every possible care must be given to the accuracy of the different tools and gages incorporated in the machine and to the accurate positioning of the dial in the different stops. If this is done, a great speed in assembling plates and reeds can be obtained.

A variation of the construction may also consist in providing means for holding the cut off reeds in proper position on their plate after they have been located there without attaching the same immediately thereafter. Such means may consist in the application of suction to the reeds located inside the blocks 703, or in the application of magnetic force in case the reeds are magnetic. Then the reeds would be only collected on the plates during their passage through stations *b* to *l* and then—on a further station to be cared for—the whole set of reeds would be attached simultaneously. This may be done by riveting or welding or soldering or clamping. In some cases the threading over of the reed hole 711 on a lug 712 with some frictional engagement will suffice to hold the reed in position, the gage 706 contributing thereto.

If welding is desired the punch may be replaced by an electrode or may comprise an electrode.

Fig. 2A illustrates a press-head 721A with punch 723A as shown in Fig. 3 but modified by a recess 750 at its lower end. This recess is adapted to accommodate the tip of the lug 712 of a plate when the punch touches the reed 710 of a plate when the punch touches the reed 710 placed on top of a plate 704. Thus the tip of the lug 712 will not be spread by the punch 723A the latter acting solely as a cut-off. This type of punch would be used in all the units *b* to *l* (Fig. 1) where the individual reeds are being collected.

Figs. 2B and 3B illustrate, by way of example, magnetic means for holding the cut off reeds 710 in place while the plates 704 in their bolster plates 703 with gages 706 are travelling through the machine. In this instance, each bolster plate 703 is provided with a groove 751 embracing the total number of slots 705 and containing a number of wires, four of which are diagrammatically shown in cross-section, which form a magnetic coil that may be electrically energized from an

appropriate electric source, not shown. In case the reed material is magnetic, the reed or reeds will be held in place by the magnetic force, in which the adjacent parts of the plate 703 and gage 706, both assumed to be of steel, play their part.

The present modification of the machine otherwise corresponds to the machine illustrated by Figs. 1, 2 and 3, with the exception that station *m* in this case not only serves for delivering the plates but also to take care of the final assembling. Therefore the unit 708A at station *m* is modified as shown by Fig. 2A. In general, only the parts differing from the unit shown in Figs. 2 and 3 are shown. Like parts are numbered alike. The press-head 721A is elongated and provided with ten solid riveting punches 723 and with ten hold-downs 722A guided in parallel slots and held conjointly by a common carrier 724A yielding supported by the head 721A through springs 747A. The punches 723 and 722 are spaced apart in conformity with the slots 706, 742 and 705. Underneath the unit 708A the vertically movable carrier 719A which is controlled in the same way as described above with reference to 719 in Fig. 2, carries ten plungers 720 individually lined up with the above mentioned slots. By operating the aforesaid modified type of assembling station, all the ten reeds 710 which have been cut off from the respective strips and located on the plates 704 while travelling from stations *b* to *l* will be attached to the particular plate by one common stroke of the multiple press-head 708A.

We claim:

1. In the manufacture of harmonicas, a machine for automatically assembling reeds and plates, comprising a plurality of bolster blocks which are movable step by step through a number of stations and adapted to receive in proper position one carrier plate at a time, to convey it, preferably together with a gage holding the carrier plate on the bolster block, to the said stations where the individual blocks, plates and gages step in alignment with stationary dies or presses for carrying out the assembling operation; a number of slots, exactly corresponding to those existing in the carrier plates, being provided in the bolster blocks and gages; a spring-loaded hold-down forming part of each of the said presses and being adapted to pass through the said slots and to engage a reed fed to a point in the path of said hold-down; at each station a plunger member adapted to pass through the slots of the bolster block and the gage (when stopped in alignment therewith) from the other side; the said plunger being adapted to engage the said reed from the opposite side and thus to allow a clamping action of the hold-down; a punch in each press, associated with the said hold-down and adapted to cut off the reed from its strip after the reed has been clamped between the said hold-down and the plunger; the said hold-down, the punch and the plunger being adapted to move conjointly, and with the cut-off reed in clamped position, through the said slots of the gage and bolster respectively towards the carrier plate until its plane is reached, the hole in the reed root, if any, being simultaneously threaded by the punch over a corresponding lug of the plate, the punch being preferably adapted then to spread the rivet or lug by pressure or heat; and a cam or equivalent drive mechanism controlling all the motions of the above parts and bringing them back into their initial posi-

tion after a cycle of operations has been carried out at the different stations during a stop of the conveyor part.

2. A machine as specified in claim 1, the punches of the individual presses however being not adapted to spread a rivet or otherwise to carry out an attaching operation, the moving bolster plates and/or gages being equipped with means for holding the individual reeds in correct position after they have been located on their plates, thus being adapted to collect step by step the whole number of reeds on each plate; and at a last station a means for attaching all the reeds together by a common operation.

3. In the manufacture of harmonicas, particularly in connection with a machine according to claim 1, the use of strips consisting of the reeds completely cut out except a connecting strip or bridge left between the reed roots.

4. A machine for assembling the reeds to the slotted reed plates of harmonicas, comprising an intermittently actuated carrier member including a plurality of holders, each being adapted to receive one of said plates in a predetermined position, and being spaced from each other according to one step of said carrier movement, a plurality of stationarily located devices for attaching reeds to a plate, the number of said devices not exceeding the number of reed slots in each of the plates, said devices being operative and arranged along the path of said carrier member in cooperative relation each to one of said holders when said carrier member is at a standstill, and being staggered with respect to each other, so as to be in registry each with a different one of the slots of a plate in a holder when the latter reaches registering positions as to said devices successively upon the stepwise movement of said carrier, and means for feeding reeds to said devices.

5. A machine for assembling the reeds to the slotted reed plates of harmonicas, comprising a carrier member stepwise movable in a closed path, at least two more holding means on said carrier than there are reed slots in the plates to be provided with reeds, each holding means being adapted to receive therein one of said plates in a predetermined position and being spaced from another according to one step of said carrier movement, a plurality of stationarily located devices for attaching reeds to a plate, the number of said devices not exceeding the number of reed slots in each of the plates, said devices being operative and arranged along the path of said carrier member and in cooperative relation each to one of said holding means when said carrier member is at a standstill, and being staggered with respect to each other so as to be in registry each with a different one of the slots of a plate in a holder when the latter reaches registering positions as to said devices successively upon the stepwise movement of said carrier, means for feeding reeds to said devices, and spaces for feeding and for withdrawing plates respectively to and from holders which at a standstill of the carrier are not in registry with one of said devices.

6. A machine for assembling the reeds to the slotted reed plates of harmonicas, comprising a stepwise movable dial serving as carrier member, at least two more holding means on said dial than there are reed slots in the plates to be provided with reeds, each holding means being adapted to receive therein one of said plates in a predetermined position and being angularly

spaced from another according to one step of said dial movement, a plurality of stationarily located devices not exceeding the number of reed slots in each of said plates, for attaching reeds to a plate, said devices being operative and arranged along

5 the path of said holding means and in cooperative relation each to one of said holding means when said carrier member is at a standstill, and being staggered in a radial direction with respect to the dial center so as to be in registry each with a different one of the slots of a plate in a holder when the latter reaches registering positions as to said devices successively upon the stepwise movement of said dial, and means for feeding reeds to said devices.

member being in operative connection with said press, and means for feeding a strip of connected reeds so as to place the reed which is the first one of the strip at a time between said counter member and said punch-like member on the one side and said support on the other side, whereby, upon operation of said press, said counter member will urge said first reed against the restraint of said support into engagement with said plate and said punch-like member will sever said first reed from said strip and press it against the plate in the holder so as to secure it thereto.

11. A method of assembling the reeds and slotted reed plates of harmonicas comprising: moving a number of consecutive plates in a predetermined position in successive steps along a predetermined path wherein the plates are spaced from each other a distance equal to one step of their path, providing strips of reeds connected near their roots, feeding simultaneously a number up to as many strips as there are reed slots in each of the plates, to as many places where plates arrive at the end of a step of their movement, cutting off one reed of each strip, applying the reed of each strip to a plate slot which is located in such plate differently from the slot to which the reed of another strip is applied, securing the applied reeds to the plates respectively, advancing the number of plates at least one step,

and repeating the process of feeding, cutting, applying and securing reeds with respect to such plates which have not been provided with a reed of each strip.

- 5 12. A method of assembling the reeds and slotted reed plates of harmonicas comprising moving a number of consecutive plates in a predetermined position in successive steps along a predetermined path wherein the plates are spaced
10 from each other a distance equal to one step of their path, providing strips of reeds connected near their roots, feeding simultaneously a number up to as many strips as there are reed slots in each of the plates, to as many places where plates arrive at the end of a step of their movement, cutting off one reed of each strip simultaneously, applying the reed of each strip to a plate slot which is located in such plate differently from the slot to which the reed of another strip is applied, advancing the number of plates one step, repeating the process of feeding, cutting and applying of reeds with respect to such plates which have not been provided with a reed of each strip, and securing the reeds of one plate simultaneously after all reeds have been applied thereto.
